SULPHANILAMIDE SOLUTION

Clarence A. Vogenthaler, Ferguson, Mo., assignor
to Donley-Evans & Company, St. Louis, Mo., a
corporation of Missouri

No Drawing. Application April 13, 1939,
Serial No. 267,619

4 Claims. (Cl. 167—65)

Within recent years there has come to the attention of the medical profession a chemical composition, or dye, known as para-aminobenzenesulphonamide, that has been found to be of very considerable value in the internal treatment of streptococcal, meningococcal, gonococcal, and other infections. For all ordinary purposes this chemical agent has been termed "sulphanilamide," and it has been observed by medical investigators, and physicians who have prescribed the composition in their practices, that in the treatment of the above named and other infections, sulphanilamide is highly beneficial.

While much is yet to be learned of the actual workings of this chemical agent, it has been determined that its value is dependent primarily on its absorption into the blood stream in sufficient quantity to reach a high concentration in a short space of time and on maintaining that high concentration over the period of treatment. 20 It has further been determined that oral administration of sulphanilamide produces a higher blood concentration than is obtained through its administration by sub-cutaneous or any other method. However, prior to this invention sulphanilamide was considered relatively insoluble (0.8% at 37° C.) and therefore in the use of this agent heretofore large doses of the drug had to be administered frequently to produce the desired high blood concentration with the result 25 that in many cases 55% to 60% of the drug was excreted in the free state.

Prior to this invention no substance was known which would act as a solvent for sulphanilamide and that could be safely taken into the human system, the sulphanilamide marketed prior to my discovery being in tablet form and in the form of powder, the tablets containing 0.3 gm. and 0.5 gm. of the drug mixed with an excipient. It was known heretofore that sulphanilamide was soluble in hot water, hot alcohol and cold acetone, slightly soluble in cold water and cold alcohol, practically insoluble in hydrochloric acid, and insoluble in ether, benzene, and chloroform. Obviously a hot solvent 30 could not be used for a sulphanilamide solution to be marketed in bottles because the sulphanilamide would crystallize out of the solution as soon as the solution started to cool. Likewise acetone, because of its nature, could not be employed as a solvent for a composition intended to be taken into the human system. Furthermore because sulphanilamide is only slightly soluble in cold water and cold alcohol these 35 mediums could not be employed as solvents in as-

much as sulphanilamide must be held in solution of not less than four percent by volume for practical purposes and the solubility of sulphanilamide in cold water and cold alcohol is very much 5 less than this.

Quite naturally the foregoing facts led to a search for some manner or means for administering sulphanilamide orally that would enable the human body to absorb it more quickly and more completely. The problem so presented has been solved by the discovery by me of an improved method in accordance with which sulphanilamide may be presented in a stable solution of approximately seven percent, by volume, which 10 is of sufficient strength to make its use practicable, and which solution as composed includes other chemical agents that are nontoxic and do not produce any chemical change in the sulphanilamide itself.

My improved method involves mixing an amount of sulphanilamide with a suitable solvent and subjecting the mixture so produced to the proper temperature for the proper period of time. It has been discovered that a solvent 15 that lends itself admirably to the production of a sulphanilamide solution in accordance with the teachings of this invention, includes glucose cut with glycerine. When such a solvent is employed and a mixture of sulphanilamide and the solvent is subjected to the proper heat treatment as disclosed herein a stable solution is produced.

As an example of the method followed in producing the improved sulphanilamide solution a mixture is made up of approximately 48% glucose; approximately 13% glycerine; approximately 5% sulphanilamide; and if required to give the desired consistency to the solution, an amount of distilled water, the percentages mentioned above being by weight. The mixture so 20 produced is slowly heated, preferably on a water bath, until it is brought to a temperature of from 75° C. to 90° C. and the mixture is held at such temperature for at least thirty minutes, being stirred as required to facilitate solution and to prevent formation of gum or jell on the surface of the mixture. After the heat is discontinued a sufficient quantity of glucose is 25 added to make up for heat loss and the resultant mixture is allowed to cool naturally. Obviously the percentages of ingredients mentioned above 30 may, under different conditions, be varied without departing from the spirit of the invention.

It has been discovered that the proper application of heat is a matter of vital importance in 35 producing a sulphanilamide solution in accord-

ance with this invention, it being absolutely essential that the mixture be subjected to the proper temperature for the proper period of time. In the absence of the proper application of heat a stable solution will not be produced even though the mixture is made up of the proper ingredients, such as those specified above, in the proper proportions.

This application is a continuation in part of an application for U. S. patent filed in my name 10 on October 1, 1937, Serial No. 166,831.

I claim:

1. The method of producing a therapeutic substance in stable solution form, which comprises producing a mixture which includes approximately 5% sulphanilamide, approximately 48% glucose, approximately 13% glycerine, said percentages being by weight, and subjecting the mixture so produced to a temperature of at least 15 75° C. for a period of time of at least thirty minutes to produce a non-toxic solution which is stable at all ordinary temperatures.

2. The method of producing a therapeutic substance in stable solution form, which comprises producing a mixture which includes approximately 20 25 5% sulphanilamide, approximately 48% glucose, approximately 13% glycerine, said per-

centages being by weight, and water, and subjecting the mixture so produced to a temperature of at least 75° C. for a period of time of at least thirty minutes to produce a non-toxic solution which is stable at all ordinary temperatures.

3. A non-toxic therapeutic substance in the form of a liquid which is stable at all ordinary temperatures, comprising a mixture that includes approximately 5% sulphanilamide, approximately 48% glucose, and approximately 13% glycerine, said percentages being by weight, said therapeutic substance being produced by subjecting said mixture to a temperature of at least 75° C. for a period of time of at least thirty minutes.

4. A non-toxic therapeutic substance in the form of a liquid which is stable at all ordinary temperatures, comprising a mixture that includes approximately 5% sulphanilamide, approximately 48% glucose, approximately 13% glycerine, said percentages being by weight, and water, said therapeutic substance being produced by subjecting said mixture to a temperature of at least 75° C. for a period of time of at least thirty minutes.

CLARENCE A. VOGENTHALER.
